UNITED STATES PATENT OFFICE.

SAMUEL W. WRIGHT, OF MOUNTAIN GROVE, MISSOURI.

TANNING COMPOUND.

SPECIFICATION forming part of Letters Patent No. 473,805, dated April 26, 1892.

Application filed August 8, 1891. Serial No. 402,070. (No specimens.)

To all whom it may concern:

Be it known that I, SAMUEL W. WRIGHT, a citizen of the United States, residing at Mountain Grove, in the county of Wright and State 5 of Missouri, have invented certain new and useful Improvements in Tanning Compounds; and I do hereby declare the following to be a full, clear, and exact description of the invention, such as will enable others skilled in the 10 art to which it appertains to make and use the same.

My invention consists in a tanning compound for tanning hides and all kinds of leather, which will be hereinafter fully de- 15 scribed and claimed.

My tanning compound consists of the following ingredients, which are combined in substantially the portions stated, namely: to ten gallons of water add five pounds of dog- 20 fennel, one ounce of muriatic acid, one ounce of blue vitriol, (copperas,) five pounds of smart-weed, five ounces of leaf-tobacco, two gallons of lye dripped from horse-manure, two pounds of wheat-flour, one pound of dried 25 ginseng-root, and one pound of hard-wood ashes, all to be thoroughly commingled and

incorporated with each other. These ingredients are to be thoroughly mingled by agitation and are then ready for use and form a most powerful and effective tanning com- 30 pound, which is employed in the usual manner for tanning all kinds of leather.

What I claim, and desire to secure by Letters Patent of the United States, is—

The herein-described tanning compound, 35 consisting of ten gallons of water, five pounds of dog-fennel, one ounce of muriatic acid, one ounce of copperas, five pounds of smart-weed, five ounces of leaf-tobacco, two gallons of lye from horse-manure, two pounds of wheat-flour, 40 one pound of dried ginseng-root, and one pound of hard-wood ashes, all thoroughly com- mingled and used in the proportions substan- tially as specified, and for the purpose set forth. 45

In testimony whereof I affix my signature in presence of two witnesses.

SAMUEL W. WRIGHT.
